UNITED STATES PATENT OFFICE.

WILFRED LEWIS, OF PHILADELPHIA, PENNSYLVANIA.

GRINDING-MACHINE.

1,119,022.

Specification of Letters Patent.

Patented Dec. 1, 1914.

Application filed November 21, 1911. Serial No. 661,511.

To all whom it may concern:

Be it known that I, WILFRED LEWIS, a citizen of the United States of America, residing in the city and county of Philadelphia and State of Pennsylvania, have invented a certain new and useful Improvement in Grinding-Machines, of which the following is a true and exact description, reference being had to the accompanying drawings, which form a part thereof.

The object of my present invention is to provide an attachment or adjunct for grinding machines and particularly for grinding machines of the kind disclosed by the patent to Frederick W. Taylor, No. 565,644, granted August 11, 1896. The purpose of the attachment or adjunct is to determine a certain angular relation between the platen or tool supporting table and the grinding wheel and for adjusting this relation to a determined value.

A more specific object of the invention is to provide a device for the purpose specified which is so constructed and arranged that it may be readily attached to existing machines of the type specified as well as initially incorporated in such machines, and which, when its use is not required may be readily so disposed that it does not interfere with the normal operation of the grinding machine.

The various features of novelty which characterize my invention are pointed out with particularity in the claims annexed to and forming a part of this specification. For a better understanding of the invention, however, and the advantages possessed by it, reference should be had to the accompanying drawings and descriptive matter in which I have illustrated and described forms of apparatus in which the invention may be embodied.

Of the drawings, Figure 1 is a perspective view of a grinding machine equipped with one form of my invention. Fig. 2 is an elevation of a portion of the grinding machine and the measuring and setting apparatus. Fig. 3 is a partial sectional elevation on the line 3-3 of Fig. 2. Fig. 4 is a partial sectional elevation on the line 4-4 of Fig. 2. Fig. 5 is a partial sectional elevation on the line 5-5 of Fig. 2. Fig. 6 is a partial sectional elevation on the line 6-6 of Fig. 2. Fig. 7 is a partial elevation taken similarly to Fig. 2 illustrating a modified construction. Fig. 8 is a section

taken on the line 8-8 of Fig. 7, and Fig. 9 is a diagram.

In the drawings, A, represents the stationary frame work or housing of the grinding machine, B, the grinding wheel; C, the supporting shaft therefor suitably journaled in the frame work A, and D, the adjustable work support or platen of the machine. As shown, the platen D is mounted on a shaft D' supported in ears E' formed on a carriage E usually made adjustable with respect to the framework A in a direction transverse to the axis of rotation of the grinding wheel. The axis of the shaft D' is parallel to the axis of rotation of the wheel B and the upper surface D² of the platen D is a plane surface parallel to the axis of rotation of the grinding wheel. The platen D may be adjusted about the axis of the shaft D' by means of an adjusting screw and hand wheel D³ carried by the latter. The tool or other body F to be ground may be mounted directly on the platen D, but preferably is clamped in a tool holder G which rests on the surface D² of the platen D. As shown this tool holder G carries a former G' adapted to bear against the normally stationary but adjustable former guide or apron A² and thereby limits the extent to which the tool is ground away and gives the tool the proper contour. An adjustably loaded lever G² and the flexible connections G³ between it and the tool holder serve to urge the latter toward the grinding wheel with the desired force. In so far as above described, the grinding machine shown is identical in substance with the grinding machine shown in the prior patent to Taylor, referred to above, and may have the various adjuncts and characteristic features suitable to or usually employed in such machines, but which it is not necessary to refer to herein.

In the use of a grinding machine of this character it is essential for satisfactory results in many grinding operations that, the plane of the tool supporting surface D² of the work support D, should be at a certain angle with reference to the grinding wheel. For instance, in grinding the end of a lathe tool having its bottom edge parallel to the surface D² of the work support, the clearance angle of the tool is determined by and is equal to the angle between the tangent to the grinding wheel at the point on the periphery of the wheel engaged by the cut-

ting edge of the tool and a line perpendicular to the surface D^2 of the tool holder, and intersecting said tangent. This is clearly shown in Fig. 9, where U represents the 5 point on the periphery of the grinding wheel engaged by the tool edge, W the tangent to the wheel at the point U , and X a line perpendicular to the surface D^2 and intersecting the tangent W , at the point U . The 10 clearance angle with which the tool will be ground under the circumstances is the angle $W-U-X$. The angle $W-U-X$ is obviously equal to the angle $Z-U-Y$ where Z represents the radial line drawn from the 15 point U to the axis of the grinding wheel, and Y , a line parallel to the work supporting surface D^2 and the plane of the grinding wheel and intersecting the line Z at the point U .

20 Variations in the height of the cutting edge of the tool above the surface D^2 and variations in the diameter of the grinding wheel, such as occurs as the latter is worn away, will change the clearance angle which 25 will be ground on the tool if the work support D is not adjusted to compensate for these variations. This is clearly shown in Fig. 9 where U' represents a point on the periphery of the grinding wheel more remote from the surface D^2 than the point U , and W' and X' represent lines intersecting at the point U' and one tangent to the periphery of the wheel and the other perpendicular to the surface D^2 of the work support. The angle $W'-U'-X'$ is obviously 30 greater than the angle $W-U-X$.

35 The point U^2 represents a point on the periphery of a grinding wheel coaxial with but of smaller diameter than the wheel to 40 which the points U and U' pertain, the point U^2 being at the same perpendicular distance from the surface D^2 of the work support as the point U . In this case the clearance angle $W^2-U^2-X^2$ ground on a tool, the cutting 45 edge of which intersects the periphery of the smaller grinding wheel at the point U^2 , would also be greater than the angle $W-U-X$. It will be apparent, however, that if the point U' were on the same grinding 50 wheel periphery as the point U but nearer the surface D^2 , and that if the point U^2 were at the same perpendicular distance from the surface D^2 as, but more remote from the axis of the grinding wheel than 55 the point U , the clearance angle obtained in either case would be less than the angle $W-U-X$. By adjusting the work support D angularly about the shaft D' as by manipulating the hand wheel D^3 , it is possible 60 to so adjust the work support for any given diameter of the grinding wheel and for any given height of tool cutting edge above the surface D^2 that any desired clearance angle within practical limits will be obtained.

65 The measuring and setting apparatus

forming the present invention comprises means for quickly and accurately determining the angle between a plane parallel to the work supporting surface D^2 and located at any desired distance above the latter, and a 70 line extending radially from the axis of the grinding wheel to the intersection of said plane with the periphery of the grinding wheel and for determining the set of the work support which will give a desired 75 clearance angle with any practical diameter of grinding wheel, and perpendicular distance between the cutting edge of the tool and the surface D^2 of the work support.

The measuring and setting apparatus 80 shown in Figs. 1 to 6 inclusive, comprises an arm H formed with arc-shaped guide rib H' on one side which is received in an arc-shaped slot A^4 formed in a flange A^3 of the stationary framework or housing of the machine. As shown, the flange A^3 is formed integrally on the cap A^{30} over one of the bearings for the grinding wheel shaft C . The slot A^4 has an internal enlarged portion A^6 receiving a curved follower H^2 . Bolts 85 H^3 secured to the follower H^2 pass through the member H and have their projecting ends surrounded by helical springs H^4 , each bearing at one end against the member H and at the other end against an abutment 90 formed by a nut H^5 threaded onto the corresponding bolt H^3 . The slot A^4 and the rib H' are concentric with the axis of rotation of the grinding wheel, and the described arrangement permits the arm H to be angularly adjusted about said axis, while the friction between the surface resiliently held in contact by the springs H^4 tends to hold the arm H in any particular angular position into which it is moved.

95 At its outer end the arm H is provided with a split bearing H^7 and a clamping screw for drawing the parts of the split bearing together by means of which a tubular member I extending transversely to, but, 100 as shown, laterally displaced from the axis of rotation of the grinding wheel, may be secured to the member H and adjusted with respect thereto in the direction of the length of the member I . The key H^8 carried by the 105 member H and entering a slot formed in one side of the member I prevents the latter from rotating about its own axis in the member H . At its outer end the member I has secured to it a transverse arm I' and the latter carries at its free end a shaft K which extends parallel to the axis of rotation of the grinding wheel. The arm I' has rigidly secured to it the sector-like quadrant member J which is provided at its peripheral edge with a scale J^2 graduated in degrees of angularity about an axis of the shaft K . As shown, the sector J is secured by means of the rivets J' in a projection I^2 115 from the arm I' proper. 120

The shaft K serves to pivotally connect the arm I' to a parallel-ruler-like gage comprising blades or links M and M' parallel to each other, and connecting blades M² and M³ which are parallel to each other, and are each pivoted at its opposite ends to the blades M and M'. The pivotal connection for the blades M and M² is formed by the shaft K. As shown, the latter has one end riveted to the blade M, and the blade M² is provided with an aperture through which the shaft K passes and is located between the blade M and the adjacent bearing surface of the member I'. To insure friction tending to hold the gage and the member I' together in any desired adjustment a helical spring L is provided which bears at one end against the member I' and at the other end against a collar K' secured to the end of the shaft K. To the blade M' is secured the lower end of a scale blade O which extends, and is formed with a slot O' extending perpendicularly to the blade M'. The blade M is formed with a longitudinal slot M⁴ and a screw P passing through the slots O' and M⁴ forms a means for clamping the blades M and O together and thereby holding the gage rigid with the blades M and M' at any desired distance apart. The blade M carries a post M⁵ at the peripheral edge of the sector J. This post is formed with an index line and in conjunction with the scale J² carried by the sector J indicates the angular relation of the blade M, and thereby of the gage as a whole to the sector J and the compound arm H I I' to which it is secured.

To bring the gage into register with the work support D the gage may be arranged to seat directly on the upper surface D² of the work support, but for convenience, in the construction shown in Figs. 1-6, this registration is effected by causing the lower edge of the blade M' to engage a pair of parallel posts or lugs D⁵ secured to one edge of the platen D.

In operation the tubular rod I is adjusted axially in the bearing H⁷ to bring the axis of the shaft K into line with the periphery of the grinding wheel, as shown in Fig. 2 and the parallel ruler device is then adjusted to bring the axis of the shaft K without altering the distance between the axes of the wheel and shaft K at the desired distance above the surface D². For convenience, the scale graduations on the scale blade O are so arranged that, when the top edge of the blade M or other index line carried by the blade is brought into register with the scale indication corresponding to the height of the cutting edge of the tool above the base of the tool, the axis of the shaft K will be displaced from the upper surface of the work support D a distance equal to the height of the tool plus the dis-

tance at which the bottom of the tool is held away from the work support by the tool holder G. In other words, by adjusting the parallel ruler device until the scale reading on the scale blade O corresponds to the height of the tool, the center line of the shaft K will be brought into line with the point at which the cutting edge of the tool contacts the periphery of the grinding wheel. After the measuring and setting device has thus been adjusted with respect to the diameter of the grinding wheel and the height of the tool, the clearance angle with which the tool will be ground for any setting of the work support, will be directly indicated by the scale graduation of the sector registering with the zero line carried by the post M⁵, and the work support D may be set to obtain the desired clearance angle by manipulating the adjusting screw D³ to bring the corresponding scale mark on the sector J' into register with said zero line. After the table has been adjusted in the manner described, the arm H may be shifted in its bearing to swing the gage proper to the rear of the machine, as shown in Fig. 1, where it remains until the wearing away of the grinding stone or a change in the height of tool being ground, or in the clearance angle desired, may make another measurement and adjustment desirable.

It will be apparent that the measuring and setting apparatus shown in Figs. 1 to 6 inclusive, consists essentially of two elements, one of which, the parallel ruler device, is a gage adapted to be brought into register with the work support and provided with a centering point (i. e. any point along the axis of shaft K) adapted to be brought into register with the periphery of the grinding wheel at the desired perpendicular distance from the work support, while the other element is an arm which extends radially from the axis of the grinding wheel to the centering point of the gage and thus furnishes an easy and accurate means for determining the angular relation between the gage and the radius and thereby the tangent to the grinding wheel at the point on the periphery of the latter in register with the centering point of the gage. The specific form of apparatus shown in Figs. 1-6, includes also provisions for readily adjusting the apparatus to fit it for a wide range of use and provisions for making the measuring and setting apparatus practically a permanent part of the grinding machine. It will be apparent, however, that the essential elements of the measuring and setting apparatus may have many variations in form and in Figs. 7 and 8 I have illustrated a modification in which the parallel ruler gage device in the apparatus shown in Figs. 1-6 is replaced by a single plate-like member Q, the lower edge Q' of which is

adapted to engage the upper surface of the work support D or the pins D⁵ if the latter be employed. The member Q is formed with a slot Q² perpendicular to the edge 5 Q'. This slot slidably receives the elongated rib J⁵ formed on a sector member JA. A bolt S and thumb nut S' form means for clamping the members JA and Q together with the index line J¹⁰ of the member 10 JA at any desired point along the scale Q¹⁰ formed on the member Q. The cylindrical head S² of the bolt S is received in a counter-bore J⁶ formed in the member JA. The head S² is formed with a slot S³ one 15 edge of which intersects the axis of the bolt S. This slot slidably receives an arm R which may be clamped in any desired adjustment by means of a clamping screw T passing through a keeper S⁴ secured to the 20 end of the bolt head S². The edge R' of the member R is intended to be set so that it extends radially from the axis of the grinding wheel and in any setting coöperates with the scale indications Q¹⁰ of the 25 sector member JA to indicate the angularity of the setting. The arm R may be pivotally connected at its inner end to the framework of the grinding machine in a manner analogous to that in which the compound arm H I I' of the construction shown 30 in Figs. 1-6 inclusive, is connected, or it may be entirely disconnected from the framework of the grinding machine, in which case it may advantageously be formed 35 as shown in Fig. 7, with a V-notch R² adapted to receive the shaft of the grinding wheel when the device is being used, in order to thereby insure the desired radial position 40 of the edge R'. The shaft S may advantageously be formed with an axial sighting passage S⁵ and the keeper S⁴ with a registering aperture S⁶ to facilitate the registration of the centering point of the gage 45 with the periphery of the grinding wheel. The operation of the apparatus shown in 50 Figs. 7 and 8 is analogous to that of the apparatus first described. The plate-like member Q in this form of the invention is brought into registry with the work support D by direct engagement of the lower edge of the member Q with the top surface D² of the member D. The centering point is adjusted to the proper perpendicular distance from the lower edge of the member 55 Q by adjusting the slide J⁵ in the slot Q² until the index line J¹⁰ is brought into line with the proper gradation of the scale Q¹⁰. The registration of the gage with the periphery of the grinding wheel is effected by 60 moving the gage along the surface D² until the axis of the passageway S⁵ is in line with the periphery of the grinding wheel. When, thereafter, the arm R is adjusted to engage the wheel shaft C, as shown in 65 Fig. 7, a measure of the desired angular

relation between the surface D² and the grinding wheel, is given by the gradation line of the scale D¹⁰ in register with the edge R' of the member R.

With the apparatus shown in Fig. 7, any 70 desired setting of the work support D may be obtained by adjusting the work support angularly to bring the edge R' into line with the corresponding gradation line of the scale Q¹⁰ when the gage is in register 75 with the work support and the periphery of the grinding wheel, as shown in Fig. 7, assuming, of course, that the member R is then in engagement with the shaft C and the passage-way S⁵ is at the proper perpendicular distance from the surface D². 80

The mode of use of the form of apparatus shown in Figs. 7 and 8 will be apparent without further explanation.

While in accordance with the provisions 85 of the statutes I have illustrated and described the best forms of my invention now known to me, it will be apparent to those skilled in the art that changes may be made in the form of the apparatus disclosed without departing from the spirit of my invention, and that certain features of the invention may sometimes be used with advantage without a corresponding use of 90 other features. 95

Having now described my invention what I claim as new and desire to secure by Letters Patent, is:

1. In a device for determining the setting of the angularly adjustable work support of a grinding machine relative to the wheel of said machine, having in combination, a gage provided with a centering point and adapted to be brought into registration with said support with said centering point in register with the periphery of the wheel and at a determined perpendicular distance from said support, and means for determining an angular relation between 100 said gage and a line radial to the wheel axis and intersecting said centering point when said registration is effected. 105

2. A device for determining the setting of the angularly adjustable work support of a grinding machine relative to the wheel 115 of said machine, having in combination, a gage provided with a centering point and adapted to be brought into registration with said support with said centering point in register with the periphery of the wheel and at a determined perpendicular distance from said support, said gage including provisions rendering it capable of adjustment to vary 120 said distance, and means for determining an angular relation between said gage and a line radial to the wheel axis and intersecting said centering point when said registration is effected. 125

3. A device for determining the setting of the angularly adjustable work support of a 130

grinding machine relative to the wheel of said machine, having in combination, a gage provided with a centering point and adapted to be brought into registration with said support with said centering point in register with the periphery of the wheel and at a determined perpendicular distance from said support, and means for determining an angular relation between said gage and a line radial to the wheel axis and intersecting said centering point when said registration is effected, said means including an arm pivotally connected to said gage to turn with respect thereto about said centering point and a scale connected to the gage for measuring the angular setting of said arm with respect to said gage.

4. A device for determining the setting of the angularly adjustable work support of a grinding machine relative to the wheel of said machine, said device comprising a gage provided with a centering point and adapted to be brought into registration with said support with said centering point in register with the periphery of the wheel and at a determined perpendicular distance from said support and means for connecting said gage to the frame of said machine said end to said gage and adapted to be centering point to be adjusted angularly about and toward and away from the axis of the grinding wheel.

5. A device for determining the setting of the angularly adjustable work support of a grinding machine relative to the wheel of said machine, said device comprising a gage provided with a centering point and adapted to be brought into registry with said support with said centering point in register with the periphery of the wheel and at a determined perpendicular distance from said support, and an arm connected at one end to said gage and adapted to be connected at the other end to the frame of said machine to turn with respect thereto about the axis of the grinding wheel.

6. A device for determining the setting of the angularly adjustable work support of a grinding machine relative to the wheel of said machine, said device comprising a gage provided with a centering point and adapted to be brought into registry with said support with said centering point in register with the periphery of the wheel and at a determined perpendicular distance from said support, and an arm connected at one end to said gage and adapted to be connected at the other end of the frame of said machine to turn with respect thereto about the axis of the grinding wheel, said

arm being adjustable to vary its effective length and thereby the distance between said centering point and said wheel axis.

7. A device for determining the setting of the angularly adjustable work support of a grinding machine relative to the wheel of said machine, said device comprising a gage provided with a centering point and adapted to be brought into registration with said support with said centering point in register with the periphery of the wheel and at a determined perpendicular distance from said support, an arm pivotally connected at one end to said gage to turn with respect thereto about said centering point and adapted to be pivotally connected at its other end to the frame of said machine to turn with respect thereto about said wheel axis, and means for measuring the angular relation between said gage and said arm. 65
70
75
80

8. A device for determining the setting of the angularly adjustable work support of a grinding machine relative to the wheel of said machine, said device comprising a gage provided with a centering point and adapted to be brought into registration with said support with said centering point in register with the periphery of the wheel and at a determined perpendicular distance from said support, an arm pivotally connected at one end to said gage to turn with respect thereto about said centering point and adapted to be pivotally connected at its other end to the frame of said machine to turn with respect thereto about said wheel axis, said gage being provided with a scale cooperating with said arm to determine the angular relation between said arm and said gage. 85 90 95

9. A device for determining the setting 100
of the angularly adjustable work support
of a grinding machine relative to the wheel
of said machine, said device comprising a
gage comprising links connected to form
a parallel ruler adjustable to vary the dis- 105
tance between parallel links, and having one
link adapted to be brought into registry
with said work support, an arm adapted to
be pivotally connected at one end to the
frame of said machine to turn about said 110
wheel axis and pivotally connected at the
other end to said gage, and a scale carried
by said gage and coöperating with said arm
to measure the angular relation between
said gage and said arm.
